(57) **CLAIM**

The ornamental design for a light emitting diode, as shown and described.

DESCRIPTION

FIG. 1 is a top plan view of a light emitting diode showing our new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a cross-sectional view thereof taken along the lines 7-7 and 7'-7' in FIG. 1.

he dashed broken lines in the drawings are for the purpose of illustrating unclaimed portions of the light emitting diode and form no part of the claimed design, and the dash-dot-dash broken lines illustrate the boundary of the claimed design.
